CONCRETE BUILDING CONSTRUCTION

Filed March 23, 1928

FIG. 2.

FIG. 1.

FIG. 3.

UNITED STATES PATENT OFFICE

WILFORD R. SPROUL, OF CHICAGO, ILLINOIS, ASSIGNOR TO E. W. SPROUL CONSTRUCTION COMPANY, OF CHICAGO, ILLINOIS, A CORPORATION OF ILLINOIS

CONCRETE BUILDING CONSTRUCTION

Application filed March 23, 1928. Serial No. 264,053.

This invention has to do with concrete building construction, and particularly with the construction of buildings with double monolithic walls with interposed heat insulation.

5 The general object of the invention is the provision of a construction and means for erecting same, whereby the thickness of the wall may be decreased by employment of 50 columns or pilasters formed therein, which pilasters or columns are heat insulated within the area of the wall.

10 Another object is the provision of means whereby a wall construction of this type may be erected rapidly and with economy of material and labor.

15 A further object is the provision of such apparatus, whereby slip forms may be employed for the building of the entire wall.

20 Other and further objects will be pointed out or indicated hereinafter or will be apparent upon an understanding of the invention or its employment in practice.

25 For the purpose of aiding in the description of the invention I show in the accompanying drawing forming a part of this specification, certain forms of construction and apparatus, but it is to be understood that these are presented for the purpose of illustration only, and are not to be construed in any fashion such as to limit the appended claims short of the true and most comprehensive scope of the invention in the art.

30 In said drawing:

35 Fig. 1 is a horizontal sectional view taken through the corner portion of a building having double monolithic concrete walls with columns therein.

40 Fig. 2 is a sectional elevation taken transversely through one of the walls therein on substantial line 2—2 of Fig. 1.

45 Fig. 3 is a part sectional elevation of a slip form and upper portion of a wall under construction, and

Fig. 4 is a cross section on substantially line 4—4 of Fig. 3.

In the construction of monolithic concrete walls, certain important advantages in speed of construction and in economy of materials and labor are gained by the employment of slip forms. As is understood by those familiar with the art, slip forms are forms in which the panels which constitute the mold surfaces for the sides of the wall are elevated from time to time as the wall is built up, to receive the pourings of concrete one on top of another.

55 In the construction of double walls, which are spaced apart for the purpose of obtaining heat insulation, economies may be effected by the forming of columns at intervals in the wall, which columns stiffen the wall and support the floors, it being possible by this means to form the portions of the wall intermediate the columns of a reduced thickness. Where effective heat insulation is desired, as in cold storage buildings and the like, these columns 60 may constitute paths of undesirable heat leakage.

65 By the present invention I provide a construction whereby monolithic walls with columns may be built rapidly by use of slip forms, and a suitable insulation of the entire wall, including the columns, may be provided. An understanding of the invention may be had most readily by reference to the examples 70 of construction and apparatus shown in the drawing. In Fig. 1 is shown a double wall construction in which the inner concrete wall 75 10 and outer concrete wall 11 are spaced apart by an intervening insulation space 12. At intervals in the wall are formed columns, made by increasing the thickness of the walls at these points; said columns constituting 80 strengthening and stiffening members in the wall and affording support for the floors 85 50. As seen in detail of Fig. 4, to form a column, the inner wall is formed with a thickened portion or pilaster 10^a which projects part way 90

across the air space 12, and the wall 11 is formed with a similar thickened portion or pilaster 11^a aligning with the portion 10^a, and an insulating slab 16 is interposed and bonded between the walls within the area of the column, the portions of the column which are integral with the respective walls being tied together by tie rods 17. Thus columns may be formed wherever desired in the wall and at the corners of the building.

In Figs. 3 and 4 are illustrated certain features of the slip forms whereby a wall of such construction may be erected. These slip forms are similar to those familiar in the art in having a number of elevating frames formed of vertical members 18 and transverse members 19, said frames being disposed at intervals along the wall, and carrying the handling platforms or runways 20 and the jack screws 21 whereby the frames and the portions carried thereby may be elevated from time to time on the jack rods 22 which extend vertically in the wall. These frames carry the outer form panels 24 and the inner form panels 25 and the intermediate form panels 26. The outer and inner form panels are arranged to constitute continuous mold surfaces defining the outer and inner surface limits of the wall, but the intermediate form panels are spaced apart at intervals to allow gaps of the widths and in the locations desired for the columns. The intermediate form panels 26 are spaced in the transverse direction of the wall by such a distance as to form the insulating space 12 of the desired width, the space between the panels being closed at the ends thereof by end plates 27. Opposite these gaps between aligning sections of the intermediate panels, the outer panel is formed with out-set portions 24^a, continuity of the same and the portions 24 being maintained by the joining strips 24^b. The various panels are maintained in parallel relationship vertically, the outer panel being supported by the suspension rods 28 and retained by the adjacent vertical frame members 18, the inner panel being supported by suspension rods 29 and retained by the other vertical frame members 18, and the intermediate panels being supported by the suspension means 30 and retained by the frame members 19.

In the construction of a building, ordinarily the slip forms will extend the full length of a wall, or around the entire extent of the enclosing walls of the entire building. The relationship of the form panels, as above described, forms a mold into which the fluid concrete is poured and allowed to set, suitable reinforcement rods being disposed in the mold cavity in the desired locations, and the forms being raised from time to time to extend the mold cavity upwardly from the portions of the wall already poured, to receive the additional pourings, this being the customary procedure in the operation of slip

forms. The concrete, of course, is suitably distributed in the mold cavities, so as to take the cross sectional form thereof. Thus, in the gaps between the sections of the intermediate panels 26, the concrete would form a monolithic bond between the outer wall 11 and the inner wall 10. In the present invention, however, this is supplemented by the interposing of insulating slabs 16 across these gaps. These slabs may be of cork, and they are of suitable width to make contact with the end plates 27 of the spaced intermediate panel sections, and are of suitable thickness to have the desired insulating effect. They are maintained in position by guides 31 carried on the form frames in position to maintain the slabs with one surface in alignment with the mold face of the outer side of the intermediate panels and the other surface outset from the mold face of the other intermediate panel. Thus the insulating slab forms part of the mold face for the inner surface of the outer wall 11, and the mold face for the outer surface of the thickened portion 10^a of the inner wall. Vertically extending reinforcing rods 32, placed in the respective wall portions opposite the gap, are tied across by the tie members 17 between ends of superimposed insulating slabs. As the forms are elevated, these slabs remain in place in the columns, forming a structural portion thereof as well as insulating inserts. The floors 15, which are subsequently poured, are bracketed into the column portions of the inner wall. The air spaces 12 between the walls may be left void, or filled with insulating material. If desired, instead of running the insulating slabs continuously, spaces may be left between the ends of the successive slabs to permit integral concrete bonds to be formed between the inner and outer wall portions at intervals.

From the foregoing explanation, it will be seen that by employment of the inventions herein described, double monolithic concrete walls may be formed with columns which are insulated within the area of the wall and having the strength necessary to carry the floors and to sustain intermediate wall portions of reduced thickness; and that the erection of such walls may be carried on rapidly, by employment of slip forms and with the resulting saving in labor and material costs.

What I claim is:

1. A slip form for double concrete wall construction comprising, in combination, form panels for molding the outer surfaces of the wall, intermediate form panels for molding the inner surfaces of the wall, said intermediate panels arranged in sections with a gap between the aligned sections, a guide on the form for maintaining a partition member across the gap, and means for elevating the form.

2. A slip form for double concrete walls comprising, in combination, outer form panels for molding the outer surfaces of the wall, one of said outer panels having its mold surface outset for a portion of its length, intermediate wall panels for molding the inner surfaces of the wall, said inner panels being disposed in aligned sections spaced to afford a gap therebetween opposite the outset portion of the outer wall panel, a guide arranged to maintain a partition member across said gap, and means for elevating the form relative to said partition member.
